BUNDLING MACHINE

John R. Rosenleaf, Enterprise, Kans., assignor to
 The J. B. Ehksam & Sons Manufacturing Company,
 Enterprise, Kans., a corporation of
 Kansas

Application August 17, 1938, Serial No. 225,304

11 Claims. (Cl. 93—93)

The present invention relates to improvements in machines for handling plaster board laths. In the present commercial art, the usual practice is to form the plaster board laths into bundles of 5 four or five laths laid one on top of the other and to secure these laths in bundles formed by means of adhesive material. Usually, this adhesive material is placed over the edges of the bundle and is caused to adhere to the edges and 10 to the top and bottom surfaces of the top and bottom laths.

The present invention relates to improvements in machines for applying the adhesive strips to the bundle and is so designed that the strips of 15 adhesive material, preferably paper, will be secured to the laths in spaced apart intervals along the sides and on the ends of the bundles.

A further object of my invention is to provide a semi-automatic machine wherein the bundle 20 is formed by the operator stacking the boards by hand and then moving the bundle to a bundling platform on which the operation of applying the strips of adhesive is performed. After the strips have been placed on the bundle, the 25 bundle is then moved off of the machine before a new stack is placed on the bundling platform.

For the purpose of disclosing my invention, I have illustrated an embodiment thereof in the accompanying drawings, in which:

30 Fig. 1 is a side elevation of the machine embodying my invention;

Fig. 2 is a plan view thereof;

Fig. 3 is a detail sectional view of one of the control valves;

35 Fig. 4 is another detail sectional view of one of the control valves;

Fig. 5 is a detail elevation of the adhesive applying mechanism;

Fig. 6 is a diagrammatic view of the air circuit 40 and electric circuit arrangement; and

45 Fig. 7 is a plan view of one of the completed bundles.

In the embodiment of the invention, I provide a suitable frame work which includes a pair of 45 bottom rails 1 mounted on suitable swivel wheels 2 to permit the movement of the structure from place to place. These bottom rails have suitable cross braces and at one end have extending upwardly therefrom, vertical angle irons 3, at each 50 corner, as well as diagonally extending angle irons 4. These angles support a top assembly frame 5 comprising the two side rails 6 which in turn support rollers 7.

A receiving frame or platform is likewise 55 formed at the opposite end of the structure which

comprises the two angle legs 8 and the two diagonally disposed angle legs 9. The legs 8 extend vertically from the rails 4 and the legs 9 extend upwardly and diagonally to support the pair of side rails 10 which, in turn, have mounted 5 thereon suitable rolls 11. Additional bracing legs, such as 12 and 13 extend upwardly from the bottom rails 1 to additionally support the platform.

A vertically movable platform is arranged between the assembly and receiving platform. This platform comprises a bed or plate 14 adapted to vertically move between the corner posts 3 and 8 and support on its top a series of rollers 15. This bed or plate is mounted upon a vertically 15 movable plunger 16 operating in a cylinder 17.

Surrounding the corner posts 8 and 3 and supported thereby, at a level slightly below the level of the assembly and receiving platforms, I provide a frame 18, in turn secured to the corner 20 post, and this frame supports a plurality, eight in number, of strip applying apparatus, designated generally by the reference numeral 19. It is to be noted that there are two of these strip applying devices at each end and two on each 25 side.

Each of these strip applying devices comprises an operating cylinder 20 having a piston 21 carrying a U-shaped yoke provided with top legs 22 and bottom legs 23. In addition to the yoke 30 which is immovably connected to the piston 21, I provide a plunger 24 biased in its outer position by a coiled spring 24' and mounted on a plunger 25 adapted to telescope the piston 21.

Associated with each of the strip-applying 35 devices 19 is a strip feeding mechanism, suitably mounted on the frame and comprising a feeding roll 26 preferably concave on its periphery and a glue applying roll 26' cooperating therewith preferably convex on its periphery and operating 40 in a glue pot 27. The feeding roll 26 is rotated in one direction, to feed the paper or other strip of material by a suitable lever 28 having a pawl and ratchet connection, of any desired type, with the roll 26 so that, looking at Fig. 5, upon the downward movement of the lever 29 the roll 26 will be rotated clockwise, while on the upward movement of the lever, the roll will remain stationary. The paper is preferably fed from a paper roll 26'' and passes upwardly between the 45 feed roll 26 and the glue roll 26' a sufficient distance to overlap the top surface of the bundle. When the paper is in this position and the piston 21 is moved to the left, looking at Fig. 5, the paper will be folded over the top and bottom 50

surfaces of the edges of the bundle, being clamped thereon by the top and bottom fingers 22 and 23 of the yoke and being pressed against the edge by the plunger 24, being held in this position by the mechanism until the glue has had sufficient time to set. On the applying stroke of the plunger 21, the paper is severed from the strip through the medium of a stationarily mounted knife blade 30 against which operates a shearing blade 31 carried on the bottom yoke member 23. Each of the strip applying devices is similar so that it is not considered necessary to describe more than one.

Each of the strip applying devices 19 is operated by fluid pressure, preferably air under pressure, and the piston 16 of the bundling platform is operated from the same source. To this end, I preferably mount on the frame 1 a pressure tank 32 which may be supplied with compressed air from any suitable source as by an air compressor or other means. This tank is connected by a suitable pipe 33 through a solenoid operated valve 34 of the type illustrated in Fig. 3, with the cylinder 17 of the platform raising apparatus 25 and leading from the valve 34 are a pair of branch pipes 35 and 36 leading respectively above and below the piston of the plunger 16.

The tank 32 is also connected with the cylinders 20 of the strip applying devices through a valve 37 likewise of the type illustrated in Fig. 3 from which extends branch pipes 38 and 38' leading respectively in front of and back of the piston of the plungers 21 of the cylinders 20 so that when air under pressure is admitted through the branch 38, the plungers of the strip applying devices will be retracted and when admitted through the branch 38' the plungers will be moved forward to strip applying position.

The solenoid control valves 34 and 37 are each of the same type as illustrated in Figs. 3 and 4. In the structure illustrated in Fig. 3, the valve casing is provided with an intake opening 39 and an exhaust opening 39' as well as a pair of delivery openings 40 and 41. These ports or openings are controlled by suitable vertically movable valves 42 and 43 mounted on a valve stem 44 which is biased in its raised or closed position by a coiled spring 45. The stem 44 projects into a pressure chamber 46 and is connected to a diaphragm 47. Pressure is admitted to this chamber 46, above the diaphragm 47 through a valve control port 48 connected by the passages 49 and 50, with the delivery intake 39. A bleed-off opening 51 controlled by an adjustable valve 52 is adapted to exhaust the chamber 46 through the passage 53.

In operation, when the solenoid 54 of this valve is energized, it raises its core 55, thereby moving the valve 56 to open position, admitting pressure above the diaphragm 47 and thereby moving the valves 42 and 43 to open position. When the solenoid 54 is deenergized, the valve 56 will be moved to closed position thus shutting off the pressure supply and the chamber exhausting through the passage 53 will permit the spring 45 to move the valves 42 and 43 to closed position.

The solenoid for the valve 37 is controlled through the medium of a suitable electromagnetically operated switch 57, the circuit of which is in turn controlled by a pair of switches 58 and 59, as will more fully hereinafter appear.

The circuit through the solenoid for the valve 34 is controlled by an electromagnetically operated switch 60, the circuit of which is con-

trolled by a pair of switches 61 and 62, purpose for which will more fully hereinafter appear. The switch 62 is operated by a stop plate 63 which is adapted to be projected through a suitable solenoid 64 into the path of the lathe bundle as it is moved from the assembly table on to the bundling table. The solenoid 64 for this stop plate 63 is controlled by a switch 65 mounted on the frame and in the path of the assembled laths as they are moved from the assembly table to the bundling table.

In operation, assuming that the bundling platform 14 has been lowered and the binding tapes applied thereto, a fresh supply of boards or laths to be bundled are stacked one on top of the other on the loading or assembling table, being evened by the side rail 66 and the end rail 67. When the stack gets to the desired height, the last board on the stack will open the normally closed switch 58. This, in turn, the switch 59, having been closed by the lowering of the bundling table, will close the circuit through the solenoid winding 68 of the control switch 57. The solenoid of the electromagnetically operated switch 57 is thus deenergized operating the control valve 37 to admit pressure through the pipe 38 and its associated branches to the front end of the cylinders 20 thus retracting the clamping yoke having the fingers 22 and 23 and the pressure plunger 21, thereby releasing the bundle on the bundling platform. One of the cylinders 20 is provided with a trip 69 and this cylinder is timed to move a little more slowly than the remaining cylinders, to insure the full retraction of the clamping yokes by the time that the trip 69 operates the switch arm or lever 70. By the time the trip 69 has engaged and moved the lever 70, all of the clamping yokes will have been fully retracted from the bundle leaving the bundle clear. The operation of the lever 70 by the trip 69 will open the normally closed switch 61, thereby deenergizing the winding 71 of the magnetically operated switch 60 and opening the circuit, which has heretofore been closed, through the solenoid controlling the valve 34. With the opening of the solenoid, the valve 34 is moved to a position to admit pressure to the bottom of the cylinder 17 and exhaust pressure from the top of the cylinder 17 thereby moving the plunger 16 and with it the bundling platform upwardly until it is level with the assembly platform. The machine is now in condition to receive a new stack of boards. As the stack of boards is moved from the assembly platform on to the bundling platform, it contacts with the normally open switch 65 thereby closing this switch. The closing of this switch energizes the circuit of the solenoid 64 thereby lowering the stop finger. As the new stack of boards is moved toward the bundling platform, it engages and operates the trip switch 66. This closes the circuit through the solenoid 64 which solenoid retracts the stop finger 63 thus permitting the taped bundle to move off the bundling platform and on to the receiving platform. This switch 65 remains closed so long as the stack of boards engages the switch. As soon, however, as the stack passes off the switch 66, the solenoid 64 becomes deenergized, permitting the stop finger 63 to be raised into a stop position, preventing the boards from overrunning the bundling table and, at the same time, the ends of the boards coming in contact with the stop finger 63 will move the stop finger to close the switch 62.

The closing of the switch 62, which is a normally

open switch, establishes a circuit through the winding 71 of the electromagnetic switch 60, thereby energizing the electromagnet controlling the valve 34 and admitting pressure to the top of the cylinder 17 and exhausting the same from the bottom of the cylinder 17 thus causing a lowering of the plunger 16 and with it the bundling platform.

As the platform 14 is lowered, it depresses the rods 29 controlling the levers 28 thereby operating the feed roll 26 to elevate an additional length of the glue strips into a position to be applied to the stacked laths. As the table 14 is lowered, it engages the normally open switch 59 closing the circuit through the winding 68 of the electromagnetically operated switch 57. This energizes the winding of the solenoid valve 37 thus moving the valve to a position to admit pressure through the pipe 38' and its associated branches to the rear of the cylinders 20 moving the pistons of the cylinders forwardly and forcing the fingers 22 and 23 of the clamping yokes over the edge of the bundle and at the same time forcing the plungers 24 against the edges of the stack so as to force the adhesive strips tightly against the edges of the stacks and over the top and bottom surfaces of the stack, thus forming a plurality of binders for holding the bundle in assembled position. The parts will thus remain in this position, permitting the glue to set, while a new stack of boards or laths are assembled on the assembling table until, as heretofore explained, the stack gets high enough for the top board to operate the switch 58, as heretofore described.

I claim as my invention:

1. In a bundling machine for applying strips of fibrous binder to the edges of a bundle of wall board laths, the combination with a bundling table, of a plurality of strip applying means disposed on each side of said table, each including a clamping yoke having the arms thereof sufficiently spaced to receive a predetermined number of stacked wall boards, a cylinder and a piston operating therein connected to each of said yokes, means for moving a gummed strip of fibrous material between the edges of said stacked wall boards and said yokes, and means for simultaneously controlling the flow of fluid pressure to said cylinders for operating said pistons to advance and retract said yokes.

2. In a bundling machine for applying strips of fibrous binder to the opposite edges of a series of stacked wall boards, the combination with a reciprocating table, means for raising and lowering said table, a plurality of strip applying devices supported adjacent the edges of said table and at a level to be opposite the edges of the stack of wall boards on said table when the same is lowered, each of said strip applying devices comprising a yoke having its fingers spaced apart sufficiently to receive between the same a stack of wall boards, means for moving a gummed strip of fibrous material between said yokes and the edges of said stack when the stack is lowered with the table and means for forcing said yokes over said strips and wall board to fold the strips on to the top and bottom surfaces of said wall board stack and force the strips against the edges of said wall board stacks.

3. In a bundling machine for applying binding strips of fibrous material to a stack of wall boards, the combination with an assembly table, of a table, means for vertically raising and lowering said bundling table to a level with an assembly table and to a level below the assembly

table, a plurality of strip applying devices disposed at the edge of said bundling table at the lower level thereof, means for moving a gum strip between each of said strip applying devices and the edge of the stack of wall boards, means for moving said strip applying devices toward and from the stack of wall boards, means controlled by the lowering of said bundling table for causing said strip applying devices to be moved toward the stack of wall boards for applying said strips, and means controlled by the stacking of the wall boards on the assembly table for causing the operating means to retract said strip applying devices from applying position.

4. In a bundling machine for applying strips of fibrous material to the edges of a stacked bundle of wall boards, the combination with an assembly table, of a bundle-supporting table, means for raising and lowering said bundle-supporting table, a plurality of strip applying devices disposed at the edge of said bundle-supporting table when the same is in its lowered position, means for moving a strip of gummed fibrous binding material between each of said strip applying devices, means for moving said strip applying devices in one direction to apply said gum strips to the wall board stack, and means operated by the movement of the wall board stack on to the bundle-supporting table for causing the operation of said raising and lowering means to lower the table to a level to receive the gummed strips.

5. In a bundling machine for applying to a stack of wall boards binding strips of fibrous material, the combination with a table, means for raising and lowering said table, means disposed at the edge of said bundling table and at its lower level for applying a plurality of strips of gummed fibrous binding material, means for projecting said applying means into applying position and for retracting the same, and means operated by the retraction of at least one of said applying means for causing said table operating means to raise the table to a receiving level.

6. In a bundling machine for applying a plurality of binding strips to the edge of a stacked bundle of wall boards, the combination with a bundle-supporting table, means for raising and lowering said bundle-supporting table, an assembly table adjacent said bundle-supporting table when the same is in its raised position, strip applying means adjacent the table when in its lower position, means for moving said strip applying means toward and from the stacked bundle of wall boards, means operated by the lowering of said table for causing said strip applying operating means to move the same into applying position, means operated by the assembly of a stack of wall boards on the assembly table for moving the strip applying means into a retracted position and means operated by the movement of at least one of said strip applying means to its retracted position for causing said table operating means to raise the table to a level with the assembly table.

7. In a bundling machine for applying strips of fibrous binding material to the edges of a stack of wall boards, the combination with a bundle-supporting table and an assembly table, means for vertically raising and lowering said bundle-supporting table to a level with the assembly table and below the level of the assembly table, strip applying means adjacent the table when the same is in its lower position, means for projecting and retracting said strip applying

- means, means operated by the lowering of said table to cause said projecting and retracting means to project the strip applying means into applying position, means operated by the assembly of a stack of wall boards on the assembly table for causing said strip applying projecting and retracting means to retract the same, means operated by the retraction of at least one of said strip applying means for causing the operation of said table operating means to raise the table, and means operated by the movement of an assembled stack of wall boards on the bundle-supporting table for causing said table operating means to lower the table.
- 15 8. In a bundling machine for applying strips of fibrous binder to the opposite edges of a series of stacked wall boards, the combination with a vertically movable table having a receiving level and a strip-applying level, means disposed adjacent the table at the strip applying level for applying strips of gummed fibrous material at the edges of the bundled boards, means operated by the movement of the table to strip applying level for causing said strip applying means to operate to apply the strips, an assembly table, means operated by the stacking of the boards to a predetermined level for moving said strip applying means to inoperative position, and means operated by the movement of said strip applying means to inoperative position for causing the movement of the table to receiving level.
- 20 9. In a bundling machine for applying strips of fibrous binding material to the opposite edges of a series of stacked wall boards, the combination with a vertically movable table having a receiving level and a strip applying level, means disposed at the strip applying level for applying strips of fibrous binder to the edges of the stacked wall boards on said table, means operated by the movement of the table to strip applying level for rendering said strip applying means operative, an assembly table, means controlled by the assembly of the wall boards to a predetermined height on said assembly table for causing the

strip applying means to be moved to operative position, means controlled by the movement of the strip applying means to an inoperative position for causing the moving of the first-mentioned table to a receiving level, and means controlled by the movement of the bundle of boards on the first-mentioned table for causing the same to move to strip applying level.

10 10. In a bundling machine for applying strips of fibrous binder to the edges of a series of stacked wall boards, the combination with a vertically movable table having a receiving level and a strip applying level, a limit stop for limiting the movement of the wall boards on to said table, means associated with said table at its strip applying level for applying binder strips to the bundle of wall boards carried by the table, means operated by the moving of the table to strip applying level for rendering said strip applying means operative, an assembly table, means operated by the stacking of the boards to a predetermined level on said assembly table for rendering said strip applying means inoperative, means rendered operative by the movement of said strip applying means to inoperative position for raising said first-mentioned table to receiving level, and means operated by the movement of the stack of boards from the assembly table to the first-mentioned table for moving said limit stop out of stopping position to permit the wall boards on the first-mentioned table to move off of the same as a new stack of wall boards is moved on the same.

15 11. In a bundling machine for applying strips of fibrous binder to the edges of a series of stacked wall boards, the combination with a vertically movable table having a receiving level and a strip applying level, a plurality of strip applying means disposed adjacent the ends and sides of the table at the strip applying level, and means for simultaneously moving all of said strip applying means to strip applying position when the table reaches its strip applying level.

JOHN R. ROSENLEAF.
